UNITED STATES PATENT OFFICE.

GEORGE H. PETERSON. OF STORY CITY, IOWA.

INTAKE MANIFOLD.

1,402,886.

Specification of Letters Patent. Patented Jan. 10, 1922.

Application filed January 24, 1920. Serial No. 353,767.

To all whom it may concern:

Be it known that I, GEORGE H. PETERSON, a citizen of the United States of America, and resident of Story City, Story County, 5 Iowa, have invented a new and useful Improvement in Intake Manifolds, of which the following is a specification.

The object of this invention is to provide means for limiting and restricting flow 10 through a manifold and particularly toward one outlet therefrom.

My invention consists in the provision of means for limiting and restricting the flow 15 of fuel mixture through an intake manifold and particularly toward one outlet therefrom.

My invention consists further in the construction, arrangement and combination of elements hereinafter set forth, pointed out 20 in my claim and illustrated by the accompanying drawing, in which—

Figure 1 is an elevation of a common form of intake-manifold, to which one form 25 of my improvement is applied. Figure 2 is a horizontal section on the indicated line 2—2 of Figure 1. Figure 3 is a vertical section on the indicated line 3—3 of Figure 1.

The drawing illustrates generally a common form of intake manifold, ordinarily employed in the Ford construction to supply fuel mixture to four cylinders arranged in a row. The manifold is constructed in a single piece of metal by molding, and comprises a neck 10 flaring from bottom to top; 35 a goose-neck 11 having a flange 12 adapted to be secured to a carbureter (not shown) and afford communication between said carbureter and the lower end of said stem; lateral arms 13, 14 communicating at their 40 inner ends with the wider upper end portion of the neck; and up-turned end portions 15, 16 on the outer ends of the arms, each of which end portions is formed with a face 17 (one of which is shown in Figure 45 3) adapted to fit a seat on an engine casing (not shown) and provided with a port registering with a port in said seat. The front and rear portions 18, 19 of the wall of the

neck 10 are differently inclined as shown. Ordinarily the cross-sections of the arms 13, 50 14 and the areas of the ports in the faces 17 are substantially alike and the flow of fuel mixture through said arms and ports is substantially equal. Experiment has demonstrated, however, that the flow through the 55 arms and ports is unequal, there being materially greater flow through the arm 14 and its terminal port, particularly under suction of the foremost cylinder and into said foremost cylinder, than through the arm 13 60 or even to the second cylinder relative to the foremost. Such greater flow provides a charge in the foremost cylinder beyond the capacity of its ignition device to explode 65 and beyond the capacity of its exhaust device to scavenge. To avoid this difficulty it is desirable to limit or restrict the flow or passage of fuel mixture through the arm 14 and experiment has demonstrated that such effect may be well produced in the manner illustrated. A slot is formed in the 70 front portion 18 of the wall of the neck 10 adjacent to the inner end of the arm 14, and a baffle plate is mounted rigidly in said slot and extends into the bore or cavity of the 75 neck. It would seem to be preferable to form the slot and insert and solder or braze the baffle plate therein as giving greater accuracy in the location of the inner edge of the baffle plate; however, the plate may be 80 formed integral with the wall by molding, or other means may be employed to effect a restriction of the flow through the arm 14, without departing from the spirit of my invention. 85

I claim as my invention—

In an intake manifold having a neck and two lateral arms leading therefrom, said neck being formed with a transverse slot, a baffle plate mounted rigidly in said slot and 90 extending within the bore of said neck adjacent to the inner end of one of said arms.

Signed at Story City, in the county of Story and State of Iowa, this 31 day of Dec., 1919.

GEORGE H. PETERSON.
